Attn:

UNITED STATES PATENT OFFICE.

CLARENCE G. SHEARON, OF EVANSTON, ILLINOIS, ASSIGNOR TO SHARP & SMITH, OF CHICAGO, ILLINOIS, A CORPORATION OF ILLINOIS.

SURGICAL NEEDLE.

Application filed June 25, 1927. Serial No. 201,337.

This invention relates to improvements in surgical needles, and more especially to such a needle particularly adapted for sewing or suturing in connection with surgical operations.

One of the features of the invention is the provision of means permitting the quick attachment of the needle of the facia, fibre, thread, string, or other material used in connection with the sewing. The needle is so constructed that, not only can the end of the facia, fibre, or thread be quickly attached thereto, but such end is securely gripped and held by the needle so that likelihood of the needle pulling loose from the thread is reduced to a minimum. The attachment of the end of the thread to the needle is also effected with little or no injury to the end of the thread, thus also diminishing the possibility of the thread pulling loose from the needle.

Other features and advantages of my invention will appear more fully as I proceed with my specification.

In that form of device embodying the features of my invention shown in the accompanying drawings Figure 1 is a view in side elevation, Fig. 2 is a view in top plan, Fig. 3 is a horizontal sectional view, Fig. 4 is a similar view, showing the jaw of the needle open, and Fig. 5 is a view similar to Fig. 3 showing a modified form.

As shown in the drawings, 10 indicates in general the point of the needle, which may be curved, as shown, or in any other form. The shank of the needle is somewhat enlarged at 11 in the usual way and the end of the needle, instead of being provided with the usual eye, has a pivoted jaw 12 mounted on a square pivot 13. The pivotal mounting is accomplished by means of a keyhole-shaped aperture 14 in the jaw 12 so that when the jaw is pushed forward as shown in Fig. 4 it may be opened. When it is slid back as shown in Fig. 3 so that the pivot 13 moves into the squared part of the keyhole-shaped aperture the jaw is held locked in its closed position.

The stationary end of the shank as indicated by 15 is grooved or hollowed out as indicated by 16 and the inner face of the jaw 12 is likewise hollowed or grooved as indicated by 17. The stationary part 15 is also preferably provided with some teeth,

claws or prongs as indicated by 18, preferably curved forwardly and the jaw 12 has similar teeth as indicated by 19. I have here shown the stationary jaw 15 as provided with two rows of such teeth, two in each row, and the movable jaw 12 has one row of two teeth, the teeth on the movable jaw adapted to lie between those on the stationary jaw when the jaw is closed.

20 indicates the end of the facia, gut, string, fibre or other material used in connection with the sewing.

In the operation of the needle, the jaw 12 is open as shown in Fig. 4, the end of the string or facia 20 is hooked over the teeth 18, the jaw 12 closed, and slid backwardly as shown in Fig. 3 to lock it. The teeth 19 and 20 will then be firmly engaged in the end of the thread 20 and hold the same firmly to the needle.

In Fig. 5 I have shown a slightly modified form in which the teeth in the movable jaw 12 are dispensed with and longer teeth 18^a are provided in the stationary jaw 15^a. The operation of this device is similar. That is, the end of the thread is hooked over the teeth 18^a and the movable jaw 12^a closed to hold it on the teeth.

The invention is especially valuable in sewing with fibres, facia and the like which are difficult to thread through the eye of a needle. By the use of my invention, also, the double thickness of the thread where threaded through the eye is dispensed with.

It will be seen that the end of my needle with the jaw when closed is no larger in diameter than the regular shank 11 of the needle. Consequently, in sewing, an unnecessarily large hole is not made as in the case where a double thickness of thread must be pulled through each hole.

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art.

What I claim as new, and desire to secure by Letters Patent, is:

1. A needle having a pointed end with a

thickened shank including a stationary part with a jaw pivoted thereto, said jaw adapted to be closed against the stationary part to grip the end of a thread therebetween, and means operated by movement of the jaw for locking the jaw in its closed position.

2. A needle having a pointed end with a thickened shank including a stationary part with a jaw pivoted thereto, said jaw adapted to be closed against the stationary part to grip the end of a thread therebetween, and means for locking the jaw in its closed position, said means including a square pivot

on the stationary part and a keyhole-shaped slot in the jaw embracing said pivot.

3. A needle having a pointed end with a thickened shank including a stationary part with a jaw pivoted thereto, said jaw adapted to close against the stationary part to grip the end of a thread therebetween, and means operated by longitudinal movement of the jaw for locking the jaw in its closed position.

In witness whereof, I have hereunto set my hand this 20th day of June, 1927.

CLARENCE G. SHEARON.
